UNITED STATES PATENT OFFICE

172,597

MILLING MACHINE UNIT

Peter M. Henkes, Racine, Wis., assignor to George Gorton Machine Co., Racine, Wis., a corporation of Wisconsin

Application October 2, 1953, Serial No. 27,064

Term of patent 14 years

(Cl. D54—14)

To all whom it may concern:

Be it known that I, Peter M. Henkes, a citizen of the United States of America, residing at Racine, county of Racine, State of Wisconsin, have invented a new, original, and ornamental Design for a Milling Machine Unit, of which the following is a specification, reference being had to the accompanying drawings, forming a part hereof.

Fig. 1 is a side perspective view of a milling machine unit taken from the left-hand side thereof showing a supporting frame structure of my design embodied therein;

Fig. 2 is a rear perspective view;

Fig. 3 is a front perspective view; and

Fig. 4 is a side perspective view thereof taken from the right-hand side of the unit.

I claim:

The ornamental design for a milling machine unit as shown.
